ENOS STIMSON, OF MONTPELIER, VERMONT.

Letters Patent No. 92,486, dated July 13, 1869.

IMPROVEMENT IN DOOR-SPRING.

The Schedule referred to in these Letters Patent and making part of the same.

To all whom it may concern:

Be it known that I, ENOS STIMSON, of Montpelier, in the county of Washington, and State of Vermont, have invented a new and improved Door-Spring; and I do hereby declare that the following is a full, clear, and exact description thereof, which will enable others skilled in the art to make and use the same, reference being had to the accompanying drawings, forming part of this specification.

This invention relates to a door-spring for holding a door either opened or closed.

It consists of two castings with flanges, by which to attach it to the door, having a recess to receive a stationary shaft, on the end of which is a ratchet-wheel with a slotted face, by which means it may be operated, being held in position by a dog in the main casting.

On the shafts of the ratchets are two flat scroll-springs, attached to said shaft, upon which they are wound, the outer ends of said springs being connected together by a link, into which the springs hook.

In the main castings is a crank-bar, which may be turned down on to the springs when the door is open, and as it shuts they take hold of side-hooks on the end of said springs, thus liberating the link, which may be readily removed.

In the accompanying drawings—

Figure 1 is a perspective view of my door-spring, as applied to a door when open.

Figure 2 is an end view of the spring and ratchet.

Similar letters of reference indicate corresponding parts.

A A represent the door and casing; B B, the main castings, with slots to receive the shafts C, with the slotted ratchets D, holding said shafts, to which are attached the scroll-springs E, which have a hook, F, on the outer end, hooking into the link G, by which the springs are connected to the crank-bars H, catching into the side-hooks i i, on the end of the springs, and releasing the link when removed.

Having thus described my invention,

What I claim as new, and desire to secure by Letters Patent, is—

1. The combination and arrangement of slotted ratchet D, spring E, hook F, and link G, in manner and for the purposes substantially as herein set forth and described.

2. The combination and arrangement of slotted ratchet D, spring E, hooks i i, and crank-bar H, substantially as herein set forth and described.

ENOS STIMSON.
